UNITED STATES PATENT OFFICE.

CARL C. JANTZEN, OF PORTLAND, OREGON, ASSIGNOR TO JANTZEN KNITTING MILLS,
A CORPORATION OF OREGON.

BATHING-SUIT.

1,390,135.

Specification of Letters Patent. Patented Sept. 6, 1921.

Application filed November 12, 1920. Serial No. 423,587.

To all whom it may concern:

Be it known that I, CARL C. JANTZEN, a citizen of the United States, residing at Portland, in the county of Multnomah and 5 State of Oregon, have invented certain new and useful Improvements in Bathing-Suits, of which the following is a specification.

This invention relates to wearing apparel and more particularly to one piece bathing 10 suits.

The primary object of the invention is directed to a novel design of bathing suit which will not bind the body and permits freedom of movement.

15 Another object of the invention is the provision of a one piece union bathing garment wherein the back of the garment is so designed as to allow freedom and comfort to the body and at the same time present a 20 neat, close fitting suit conforming to the accepted styles of this type of garment.

Another object of the invention relates to 25 an exclusive design of bathing suit including a novel form of gusset which allows freedom of the body and will not bind or draw on the trunks of the suit when wet.

With these objects in view and others 30 which will be manifest and suggested as the nature and purpose of the invention are revealed in the following specification and drawing wherein I have shown a practical, yet preferred embodiment thereof,

Figure 1 is a front view of the garment.

Fig. 2 is a front view of the trunk portion 35 of the garment.

Fig. 3 is a rear portion of the trunks.

Fig. 4 is a detached view of the gusset.

Fig. 5 is a section through the leg and crotch portion of the garment.

40 Similar numerals in the specification referring to like and corresponding parts on the drawing, numeral 1 designates the body and 2 the trunks of the union garment which are made of elastic, closely woven material which permits the same to be 45 stretched in all its parts and therefore adjustable to any form and does not sag when wet. The body and trunk portions of the garment are sewed on the dotted line 3, just 50 below the waist line 4 as clearly shown in Fig. 1 of the drawing.

Referring now to Fig. 2 it will be seen 55 that the back of the trunks are made longer than the front and are cut semi-circular as indicated at 5 which gives the bathing suit sufficient fullness in the back to permit free-

dom of the body and consequently does not bind the person, a common objection of modern designs of bathing suits. It will of course be understood that the width of the 60 semi-circular portion 5 will vary with the size of the suit but in all instances, this portion of the trunks will allow for the necessary pull on the garment incident to distortions of the body while swimming or 65 engaging in strenuous exercise.

The gusset indicated at 6 is stitched at 7 to the leg portions 8, 9 and the seat 10 of the trunks, it being observed that the rear sides 11, 12 of the gusset are substantially twice 70 the length of the front portion thereof and consequently allows for freedom of the body and does not bind in the seat portion of the trunks. Due to the elasticity of the material the gusset and semi-circular portions 75 of the trunks permits perfect freedom of the body without pull on the garment which in all instances will cling to the body and will not bind in the seat or back, particularly when the garment is wet.

80 In the accompanying drawings, I have illustrated my invention embodied in one form by way of example, and which in practice has been found to be highly satisfactory in obtaining the desired results. It 85 will be obvious however that other embodiments may be adopted, and that various changes in the details of construction may be resorted to by those skilled in the art without departing from the spirit and scope 90 of the invention. It is furthermore understood that the invention is not necessarily limited or restricted to the precise elements shown except in so far as such limitations are specified in the subject matter being 95 claimed.

What I claim is:

In a one piece bathing garment of the class described, a body, a trunk portion attached thereto, the rear waist line of said 100 trunk portion being cut along a curved line and stitched to the body, whereby the rear of the trunk portion is longer than the front thereof, a substantially triangular gusset, twice the length at the rear of the 105 garment than at the front thereof stitched to the trunk portion to allow for binding in the seat and back of the garment due to distortion of the body.

110 In testimony whereof I affix my signature hereto.

CARL C. JANTZEN.
